(57) **CLAIM**

The ornamental design for a hard disk video recorder, as shown and described.

DESCRIPTION

FIG. 1 is a front perspective view of a hard disk video recorder showing our new design.

FIG. 2 is a rear perspective view of the hard disk video recorder.

FIG. 3 is a front view of the hard disk video recorder.

FIG. 4 is a rear view of the hard disk video recorder.

FIG. 5 is a left-side view of the hard disk video recorder.

FIG. 6 is a right-side view of the hard disk video recorder.

FIG. 7 is a top view of the hard disk video recorder; and,

FIG. 8 is a bottom view of the hard disk video recorder.

The broken lines immediately adjacent the shaded areas represent the bounds of the claimed design while all other broken lines are directed to environment and are for illustrative purposes only; the broken lines form no part of the claimed design.

The “ezviz” trademark forming part of the claimed design, in FIGS. 1, 2, and 7, is a registered trademark of Hangzhou Hikvision Digital Technology Company, Ltd.

1 Claim, 4 Drawing Sheets
